7 Claims. (Cl. 68—210)

ABSTRACT OF THE DISCLOSURE

The present disclosure sets forth a cover combination for a washing and centrifuging machine, which has a swinging outside cover for the receptacle and a retractable inside cover for the drum. The outside swinging cover is provided with a recess in which the retractable cover is positioned upon the opening and from which it is projected against the drum during washing and centrifuging.

The present invention relates to a cover for a washing and centrifuging machine and it particularly relates to a cover arrangement which may be employed for securely covering such a washing and centrifuging machine when in operation and at the same time be readily opened so as to permit ready discharge of material therefrom or supply of new material to be processed therein.

Although not limited thereto, the present invention will be particularly described in its application to the use of hydraulic or pneumatic cylinders for the opening or closing of housings or drums for clothes or textile washing and centrifuging machines.

Such covers must be designed so that they will securely close the opening of the housing as well as the opening of the drum or basket rotatably arranged in the housing so that any treating liquids will be securely retained therein without leakage and so that liquids and steam may be readily supplied thereto.

It is also important that the textile materials or other fabrics or clothing being processed in the rotating drum or centrifuge be held within the drum and not be permitted to emerge from the drum during the washing or treating procedures with lodgement between the inner wall of the housing and the outer wall of the drum or basket.

It is not altogether satisfactory to provide separate covers for closing the drum opening and the housing opening. This operation provides for a double pivot system and double lever system and requires double locking and there is the further difficulty that the drum cover must be connected with the drum by linkages or levers which interfere with the loading and unloading of the rotatable drum.

If an altogether detachable or separate cover is provided for the drum or basket there is always the possibility and likelihood that one may forget to close the rotating drum with the lodgement of the clothes or laundry between the outside of the drum and the inside of the housing. Furthermore, where a cover is provided which jointly closes both the housing opening and the rotatable drum opening, such cover must be with difficulty articulated in respect to the housing and it is difficult to actuate such articulated cover so that both closures are achieved. This is particularly so where the cover for the drum must have a different diameter than the cover for the housing and where the pivotal mountings must be necessarily differently positioned for each cover.

Furthermore, such articulated or spaced covering devices will interfere with loading and unloading of the rotatable drum or basket unless they are swung out of

2

position by at least 180°, which is quite difficult with normal hydraulic or pneumatic cylinders.

It is among the objects of the present invention to provide a swinging cover which only requires a limited motion of not over 90° and which will not interfere with the loading and unloading procedures but will provide slideways or guideways facilitating the same.

Still further objects and advantages will appear in the more detailed description set forth below, it being understood, however, that this more detailed description is given by way of illustration and explanation only and not by way of limitation, since various changes therein may be made by those skilled in the art without departing from the scope and spirit of the present invention.

In accomplishing the above objects it has been found most satisfactory to provide a recessed cover in which is provided a recess receiving a reciprocal pot or insert or inside cover which when the recessed outside cover is closed may be extended inwardly to serve as a cover for the rotatable basket and when the cover is swung outwardly will be retracted into the said recess and form a smooth surface for enabling discharge or supply of textile material or clothing into or from the basket.

In one preferred form of the invention pneumatic cylinders with piston rods will actuate the cover so as to press the pot or insert into the cover when the cover is open or to pull it into the recess in the opening of the basket or rotating receiver when the cover is closed. Thus it is possible by a single pair of pneumatic cylinders with their piston rods to actuate the cover and both sides of the apparatus without any actuating means for the reciprocal pot or insert.

This may be accomplished by providing guide pins or rods which will extend outwardly to both sides of the housing and prevent canting thereof in its closing and opening operations.

An important feature of the present invention resides in the fact that the pot or insert may be so connected with an exterior conduit system so as to feed liquid treating agents and steam into the interior of the rotatable drum and cylindrical housing of the washing or centrifuging machine. The portion of the insert or pot closing the opening of the basket or drum may be provided with the means to feed the steam and treating fluids directly into the interior of the basket.

This will assure acceleration of the washing and rinsing processes and also aid in more uniform penetration from inside to outside of the fluids from the inside of the drum to the outside through the textile material or clothes therein. This greatly shortens the time required for permeation of the textile materials or clothing by the washing agent.

With the foregoing and other objects in view, the invention consists of the novel construction, combination and arrangement of parts as hereinafter more specifically described and illustrated in the accompanying drawings, wherein is shown an embodiment of the invention, but it is to be understood that changes, variations and modifications can be resorted to which fall within the scope of the claims hereunto appended.

In the drawings wherein like reference characters denote corresponding parts throughout the several views:

FIG. 1 is a diagrammatic inside plan view of the inside of the cover of the washing and centrifuging machine.

FIG. 2 is a diagrammatic side view of the washing and centrifuging machine with the cover in closed position.

FIG. 3 is a diagrammatic side view similar to FIG. 2 showing the cover open and in unloading position.

Referring to FIG. 1, the cover A has a rectangular base portion 1 which will close off the opening of the cylindrical housing B having the top plate C and the base plate D. Within the housing is the rotating drum or basket

E driven through the base F and the shaft G. The rectangular cover structure 1 carries the cylindrical insert closure portion 2 which will be inserted into and close the circular opening 50 of the housing B.

The insert 2 is provided with the laterally extending guide pins or rods 4 and 5 which are located on opposite sides of the insert 2 and which slide in the grooves 6 and 7 in the end elements 51 and 52 mounted on the underside 3 of the rectangular structure 1.

A transparent window 9 is provided on the center portion 8 of the insert 2. This window may coincide with a transparent window 10 on the outside face 53 of the cover structure 1.

Hollow supporting arms 11 and 12 extend beyond both end edges 54 of the cover structure 1 and at their ends they are provided with the conduits 13 and 14.

As indicated in FIG. 3, the conduit 14 will extend downwardly from the cover structure 1 alongside of the housing B and it will lead to the conduit 16 for supplying steam that may be fed into the housing B. At the other side leading to the conduit 13 will be the conduit 13 for supplying wash and rinsing water and also various detergent or other solutions.

The inside ends 54 and 55 of the hollow arms 11 and 12 which communicate with the conduits 13 and 14 are provided with the openings 17 and 18 which permit passage of the fluids into the interior of the insert or pot 2 from whence the fluids, whether it be steam or liquid, pass through the perforations 19 in the bottom 8 of the pot or insert 2 into the inside of the container B and rotating drum E.

The underside of the hollow arms 11 and 12 adjacent the connections of the conduits 13 and 14 are provided with the pivotal connections 20 and 21 beyond the edges 50 and 54 of the cover structure 1.

The piston rods 22 actuated from the hydraulic or pneumatic cylinders 23 are connected to the pivotal connections 20 and 21. The cylinders 23 are pivotally mounted at 24 on the sides 56 of the cylindrical housing B.

To support the cover structure A there is provided on the side of the housing B below the opening 50, a shaft 25 supported on the ends thereof around which the cover structure is swung as shown from the position of FIG. 2 to the position of FIG. 3, and reversibly.

During the washing and centrifuging operation, the cover A will be closed as shown in FIG. 2. After the washing and centrifuging operation is completed hydraulic or pneumatic pressure may be applied to the cylinders 23 positioned at each side of the housing B and the piston rods 22 will be moved outwardly first to push the insert or pot 2 into the inside of the cover 1 as shown in FIG. 3 until the bottom face 8 of the pot or insert 2 will be flush with the inside face of the cover A as shown in FIG. 3 and form a flat surface.

Thereupon, the pins or rods 4 and 5 will transmit the force of the piston rods 22 to the cover structure A until the cover is swung outwardly about 90° around the shaft 25 until the edge 57 of the cover A adjacent the pivot 25 will contact or be stopped by the supporting block 26 on the end face C of the housing B.

When this is accomplished the inside face of the cover A as shown in FIG. 3 will form a discharge surface or slide surface by which the contents of the rotating drum or basket E may be removed. To load the basket or drum E again the apparatus as shown in FIG. 3 with the cover in 90° open position may be moved up 90° so that the inside face of the cover A will then form a chute for the loading process.

When the drum E has been filled after emptying, the piston rods 22 are retracted into the cylinders 23 and the cover structure A is pulled down onto the housing B and the pot or insert 2 is pulled into the opening 50 while guided by means of the rods or pins 4 and 5.

The length of the grooves 6 and 7 will limit the movement of the insert 2. When the pot or insert 2 is pulled

into the opening as shown in FIG. 2, its bottom or inside face 8 will form a flush surface with the inside face 58 of the basket or drum E.

The projecting sides and edges of the cover A beyond the pot or insert 2 will rest upon the ceiling ring 28 of rubber or other elastic material and thus seal off the washing liquor space within the basket E and within the drum B.

It is thus apparent that the applicant has provided a simple effective readily actuated and manipulated cover opening and closing arrangement for large washing and centrifuging machines which may be readily modified in accordance with the scope of the present application.

What is claimed is:

- 15 1. In a washing and centrifuging machine for laundry and textile articles of the type having a swinging cylindrical receptacle having a top side and a bottom side, a motor drive shaft axially mounted in said bottom side, a rotary drum positioned within said receptacle driven by said shaft, said drum having a closed bottom side connected to the shaft and a top side having a central filler and discharge opening, said top side of the receptacle also having a central opening to permit access to the central filler and discharge opening of the drum and to permit charging and discharging of the rotatable drum, said receptacle being held with its axis horizontal during washing and centrifuging, with its axis inclined upwardly through the top during charging and with its axis inclined downwardly through the top wall during discharging; the combination therewith of a swinging cover for said top side of the receptacle, a retractable cover for the top side of the drum, a recess in said swinging cover to receive said retractable cover when the swinging cover is moved to discharge position and means to close said covers against said openings on the top side of the receptacle and drum during washing and centrifuging and whilst projecting retractable cover into the opening in the drum to close the same and to swing the covers away from the openings during charging and discharging, said swinging cover having outwardly extending arms leading into the retractable cover and said arms having pivotal connections beyond the swinging cover and actuating piston and cylinder means associated with said pivotal connections.
- 20 2. The machine of claim 1, said last mentioned means consisting of pneumatically operated cylinders provided with piston rods on each side of the receptacle.
- 25 3. The machine of claim 1, said retractable cover consisting of a hollow pot member having liquid and steam connections for feeding liquid and steam into the drum and perforations on the inside of the retractable cover to permit flow of liquids and steam into the interior of the drum.
- 30 4. The machine of claim 1, said retractable cover being cylindrical and said swinging cover being rectangular and having a central recess in said retractable cover and guide members in said swinging cover to control and guide the movement of the retractable cover and prevent canting thereof.
- 35 5. The machine of claim 1, the bottom wall of the retractable cover being flush with the bottom wall of the swinging cover when said covers are away from the openings during charging and discharging.
- 40 6. The machine of claim 1, said outer swinging cover having guide means on the outside thereof to guide the movement of the retractable cover.
- 45 7. The machine of claim 1, the outside swinging cover being provided with a central transparent window and said inside retractable cover having a coinciding window on its inside face.
